ROY T. AXE, OF SYRACUSE, NEW YORK, ASSIGNOR TO OLIVER M. EDWARDS, OF SYRACUSE, NEW YORK.

SPRING-ROLLER.

1,145,962.

Specification of Letters Patent. Patented July 13, 1915.

Application filed May 25, 1911. Serial No. 629,299.

To all whom it may concern:

Be it known that I, Roy T. Axe, of Syracuse, in the county of Onondaga and State of New York, have invented a certain new and useful Spring-Roller, of which the following is a specification.

My invention has for its object the production of a spring roller for raising windows, curtains, etc., which is particularly simple in construction, economical in manufacture, and highly efficient and durable in use; and it consists in the combinations and constructions hereinafter set forth and claimed.

15 In describing this invention reference is had to the accompanying drawing in which like characters designate corresponding parts in all the views.

Figure 1 is a longitudinal sectional view, 20 partly broken away, of a roller embodying my invention. Fig. 2 is a cross sectional view on line "A—A" Fig. 1. Fig. 3 is an end view of one of the axles of the roller.

1 is the body of the roller, the same being 25 a metallic cylindrical shell formed of a strip of sheet metal rolled into cylindrical form, and having the edges thereof interlocked as shown at 2, Fig. 2.

3 is a head at one end of the cylindrical shell 1 for supporting one of the axles of the roller, and 4 and 5 are heads in the other end portion of the shell 1 for supporting the other axle. The head 3 is composed of sheet metal and comprises a discoidal body 35 having an annular or cylindrical marginal flange 6 extending within the shell 1 and fitting the inner face thereof, and also having an axial opening, the margin 7 of the wall around the axial opening being turned 40 inwardly forming a hub or bearing for the axle to be described. The free edge of the annular flange 6 abuts against an internal shoulder 8 consisting of a circumferential corrugation in the shell 1, and said head is 45 held in position by turning the margin at one end of the shell 1 inwardly on the outer face of the head 3 as indicated at 9. The flange 6 is formed with openings 10 which are alined with openings 11 formed in the 50 contiguous end of the shell 1 and spaced around the same.

The head 4 is located near the extreme end of the shell 1 opposite to that provided with the head 3, and the head 5 is located some distance within the shell 1 and is 55 spaced apart from the head 4. Each of the heads 4, 5 consists of a sheet metal disk fitted to the shell 1 and having an axial offset portion 12 or 13 formed with openings for receiving the axle 14. The head 5 60 abuts against an internal annular shoulder 15 formed in the same manner as the shoulder 8, and the head 4 is held in position by the inturned margin 16 of the end of the shell 1, and such heads 4, 5 are spaced 65 apart by the interposed portion of the axle 14 which is provided with integral shoulders 17 pressed therefrom and engaging the opposing faces of the disks 4, 5 or the offset parts 12, 13 thereof for holding 70 the heads 4, 5 against the inturned margin 16 and the shoulder 15. The axle 14 is rotatable with the shell 1 and is provided with a stud or trunnion 18 outside of the shell. The construction of the end of my 75 roller provided with the heads 4 and 5 and the axle 14 is fully described and claimed in my Patent No. 1,049,036, issued Dec. 31, 1912, upon an application divisional hereof.

19, 20 are the members constituting the 80 anchor for the spring of the roller, each of said members preferably having a discoidal head and an annular cylindrical flange, the heads being spaced apart and constituting the end heads of the anchor, the flanges 85 projecting from the margins of the opposing side faces of the heads, and the flange of one member fitting the inner face of the shell 1 and the flange of the other member telescoping within the flange fitting the 90 shell 1. The members 19, 20 are also formed with a bearing for the axle to be described. In the illustrated embodiment of my invention, the member 19 is formed with an annular cylindrical flange 21 fitting the 95 shell 1 and projecting laterally from one side face of the main part of the member 19, and with an axial inset boss 22 projecting from said side face; and the member 20 is formed with a flange 23 fitting 100 within the flange 21 and abutting at its free edge against the head of the member 19, and

the member 20 is also formed with an axial opening 24. The members 19 and 20 are secured to the shell 1 by suitable fastening means 25 extending transversely through the shell 1 and the flanges 21 and 23.

26 and 27 are elements of the axle, which is fixed from rotation with the shell 1 in the normal operation of the roller, the section 26 being journaled in the bearing 7 of the head 3 and having at its outer end a trunnion 28 projecting beyond the outer face of the disk 3, and the section 27 comprising a sleeve receiving a portion of the section 26 arranged on the inner side of the bearing 7, the section 27 extending through and being journaled in, the opening 24 of the anchor disk 20, the inset boss 22 of the member 19 of the anchor extending into the axial passage of said section 27 and the end edge of the section or tube 27 surrounding such axial passage being seated against the opposing surface of the anchor member 19 and around the boss 22.

29 is a torsion spring coiled about the axle section 27 and having a portion 30 at one end extending through openings 31 and 32 in the heads of the anchor members 19 and 20 in order to secure the spring to such anchor, the opposite end of the spring being extended through the section 27 and into the section 26 as indicated at 33.

34 is a discoidal head formed of sheet metal and mounted on the axle section 26 and rotatable therewith, said head 34 having a cylindrical marginal flange 35 extending outwardly within the flange 6 of the head 3 and having openings 36 designed to be brought into alinement with the openings 10 and 11 of the flange 6 and the shell 1 respectively. The head 34 is secured to the section 26 and is provided with lugs 37 projecting into its axial opening, each lug 37 fitting lengthwise peripheral grooves 38 formed in the section 26.

45 After the parts of the roller have been assembled, the spring is tensioned by turning the axle section 26 by a suitable tool engaged with the trunnion 28, and the spring is held under tension until the roller has been mounted in position and the window or curtain connected thereto. The spring is held under tension by means of a suitable locking member inserted through the aligned openings 11, 10 and 36. When the roller has been placed in position and the window or other parts attached thereto, such locking member is removed permitting the spring to exert its tension on the part connected to the shell 1. This spring roller is economical of manufacture in that the cylindrical shell, the heads, anchor and other parts thereof are formed of sheet metal.

What I claim is:—

1. A spring roller comprising a metallic

shell, an anchor located within the shell and including a pair of spaced apart opposing end heads, one being provided with an axial opening, an axle extending into the shell and being journaled in said axial opening and seated against the end head of the anchor opposed to said head provided with the axial opening, and a spring having one end secured to the anchor and its other end secured to such axle, substantially as and for the purpose set forth.

2. A spring roller comprising a metallic shell, an anchor located within the shell and including a pair of spaced apart opposing end heads, one being provided with an axial opening, and the other being provided with an axial boss projecting toward said head provided with the axial opening, an axle extending into the shell and being journaled in said axial opening, the axle having an axial passage opening through its inner end for receiving the boss, the inner end of the axle being seated against the opposing surface of the head provided with the boss, and around the boss, and a spring having one end secured to the anchor and its other end secured to such axle, substantially as and for the purpose described.

3. A spring roller comprising a metallic shell, an anchor located within the shell and including members having opposing parts forming opposing end heads of the anchor, said members being provided with annular telescoping parts secured to the inner face of the shell, the anchor being formed with an axial bearing, an axle extending into the shell and having its inner end coacting with said bearing, and a spring having one end secured to the anchor and its other end secured to such axle, substantially as and for the purpose specified.

4. A spring roller comprising a metallic shell, an anchor located within the shell and including members having opposing parts forming opposing end heads of the anchor, said members being provided with marginal annular flanges projecting from the opposing faces of said members and telescoping with each other, the flanges being secured to the inner face of the shell, and the end edge of the inner flange projecting from one of said members being seated against the opposing face of the other member, the anchor being formed with an axial bearing, an axle extending into the shell and having its inner end coacting with said bearing, and a spring having one end secured to the anchor and its other end secured to such axle, substantially as and for the purpose set forth.

5. A spring roller comprising a metallic shell, an anchor located within the shell and including members having opposing parts forming opposing end heads of the anchor, said members being provided with annular

- telescoping parts secured to the inner face of the shell, one of said members being provided with an axial boss, an axle extending into the shell and having an axial passage 5 opening through its inner end for receiving the boss, the end edge of the axle surrounding the inner end of the passage being seated against the opposing face of the member provided with the boss, and around the base 10 of said boss, and a spring having one end secured to the anchor and its other end secured to such axle, substantially as and for the purpose described.
6. A spring roller comprising a metallic shell, an anchor located within the shell and including members having opposing parts forming opposing end heads of the anchor, said members being provided with annular telescoping parts secured to the inner face of the shell, one of said members being provided with an axial opening, an axle extending into the shell and being journaled in said axial opening and seated against the end head of the anchor opposed 25 to said head provided with the axial opening, and a spring having one end secured to the anchor and its other end secured to such axle, substantially as and for the purpose specified.
7. A spring roller comprising a metallic shell, an anchor located within the shell and including members having opposing parts forming opposing end heads of the anchor, said members being provided with marginal annular flanges projecting from the opposing faces of said members and telescoping with each other, the flanges being secured to the inner face of the shell, and the end edge of the inner flange projecting 35 from one of said members being seated against the opposing face of the other member, one of said heads being provided with an axial opening, and the other being provided with an axial boss projecting toward 40 said head provided with the axial opening, an axle extending into the shell and being journaled in said axial opening, the axle having an axial passage opening through its inner end for receiving the boss, the 45 inner end of the axle being seated against the opposing surface of the head provided with the boss, and around the boss, and a spring having one end secured to the anchor and its other end to such axle, substantially 50 as and for the purpose set forth.
8. A spring roller comprising a rotatable shell, an axle extending into the shell and being designated to be fixed from rotary movement with the shell, a head at one end 55 of the shell having a bearing journaled on the axle, said head having an annular flange fitting the inner face of the shell, such flange and shell being formed with alined openings, and a head provided on the axle hav-
- ing an annular flange within the annular flange of the head, the inner flange being formed with openings adapted to be alined with the former alined openings, and a spring encircling the axle and being secured at one end to the axle and at its opposite end 70 to the shell, substantially as and for the purpose set forth.
9. In a spring roller and in combination, a shell having openings extending therethrough and spaced around the same adjacent one end thereof, an anchor fixed within the shell, an axle journaled in the anchor, disks in the shell provided with complementary marginal flanges having openings for registering with each other and with said 80 openings in the shell, one of said disks being fixed in the shell and the other to the axle, and both being provided with openings for the reception of the axle, and a spring coiled about the axle and fixedly connected at one 85 end thereto and at its other end to said anchor, substantially as and for the purpose described.
10. In a spring roller and in combination, a shell having openings extending therethrough and spaced around the same adjacent one end thereof, an anchor fixed within the shell, a disk closing one end of the shell and provided with an inwardly extending marginal flange provided with openings registering with the openings in the shell, said disk also being provided with an axial opening, an axle having one end journaled in the anchor and its other end journaled in said axial opening, a second disk 95 fixed to the axle and provided with an outwardly extending marginal flange located within the flange of the first-named disk and provided with openings for registering with the openings in the flange of the first-named disk, and a coiled spring connected at one end to the axle and at its opposite end to the anchor, substantially as and for the purpose specified.
11. In a spring roller and in combination, a shell, a disk mounted in one end thereof and provided with an axial opening and a marginal flange, an anchor fixed within the shell, an axle including two parts, one a tube having one end supported by the anchor, and the other part having a portion extending through said axial opening, and another portion extending within the bore of said tube and provided with a peripheral lengthwisely extending groove, a second 110 disk mounted on the second-named part of the axle, the last-named disk having a portion extending into said peripheral groove for preventing relative turning movement of the second disk and said axle, the second 115 disk being provided with a marginal flange extending within the flange of the first-mentioned disk, and said flanges, and the shell
- 120
- 125

being provided with openings adapted to register with one another, and a spring connected at one end to said anchor and at its opposite end to the axle, substantially as and for the purpose set forth.

In testimony whereof, I have hereunto signed my name in the presence of two at-

testing witnesses, at Syracuse, in the county of Onondaga, in the State of New York, this 22nd day of May, 1911.

ROY T. AXE.
